NEEDLE THREADER FOR A SEWING MACHINE

Isao Masuyama, Iishioka-shi, Ibaragi, Japan, assignor, by mesne assignments, to Belcon Importing Co., Los Angeles, Calif.

Application April 7, 1958, Serial No. 724,662

Claims priority, application Japan June 17, 1957

7 Claims. (Cl. 112—225)

The present invention relates to an improvement in a needle threader for a sewing machine, and more particularly to an improvement in a needle threader of the type wherein a hook-needle is advanced so as to pass through an eye of a sewing-needle of the sewing machine while said sewing-needle is guided by a guiding channel of the threader.

A needle threader, according to the present invention, is characterized in that a needle guiding plate is mounted in a little inclined position downwardly to the front and has a first guiding channel of inverted V section for guiding a hook-needle and a second guiding channel of V shape at its forward end for guiding a sewing needle of the sewing machine, the said second channel being formed by cutting off the sides of the channel in the forward end from the top to the bottom in inclined direction, and the slideable hook-needle which has a hook portion at the front bending upward at a proper angle is so arranged that the upper edge of the hook portion is always lightly pressed into contact with the top of said hook-needle guiding channel.

The object of the present invention is to guide the hook-needle so that only the upper edge of the forward end hook portion is kept in contact with the top of the first guiding channel, and to make the forward end of the top of the first guiding channel conform to the apex of the V-shaped second guiding channel, whereby the hook-needle can be positively and easily passed through the eye of the sewing-needle. (The hook-needle is positively passed through the eye of the sewing-needle without fail, even if the hook-needle is somewhat bent.)

The other object is to make the upward bending angle of the hook portion of the hook-needle substantially accord with the inclining angle of the needle portion of the hook-needle when the hook portion slides into the eye of the sewing needle, so that the hook portion passes into said eye substantially at a right angle with respect to the sewing-needle, thereby facilitating the passing of the hook needle, as well as permitting the vertical width of the hook portion of the hook-needle to be made somewhat longer than usual, thus facilitating the manufacturing of the hook-needle.

In order that the present invention can be clearly understood, it will be explained with reference to the accompanying drawings which illustrate, by way of example, one embodiment of the present invention, in which:

Fig. 1 is a perspective view of a needle threader according to the present invention;

Fig. 2 is a side view of the needle threader attached to a pressure-bar of a sewing machine and kept in its operative position, the pressure-bar being shown by chain lines;

Fig. 3 is a sectional view taken along the line III—III of Fig. 1;

Fig. 4 is a side view of the needle threader in the raised position;

Fig. 5 is an end view of the needle threader as seen from the right side of Fig. 2, showing the lowered position by full lines and the raised position by chain lines;

2

Fig. 6 is a perspective view of a hook-needle;

Fig. 7 is a plan view of the needle guiding plate, showing a sewing-needle in cross section;

Fig. 8 is a view taken along the line XIII—XIII of Fig. 7; and

Fig. 9 is a view illustrating the relation between the sewing-needle and the hook-needle.

Referring to the drawings, the needle threader according to the present invention comprises a threader proper indicated generally by the reference numeral 1 and a mounting member generally indicated by the reference numeral 2.

As shown in Figs. 1, 2 and 3, the threader proper 1 comprises a base plate 3 slightly tilting downward to the front, a supporting plate 4 and a needle guiding plate 5. A slider 6 is slidably mounted on the base plate 3 so that it can be slid along a slot 7 formed in said base plate. A spring 8 is provided which is fixed at one end on the supporting plate 4 and is engaged at the other end with a pin 9 which is mounted on the slider 6. The spring 8 always acts to push the slider 6 backward along the slot 7 and to hold it in its retracted position. A hook needle 10 is releasably mounted at the rearward end on the slider 6.

Said needle guiding plate 5 has on its underside a first guiding channel 11 having inverted V-shaped section for guiding the hook-needle 10 (Fig. 8), and at its forward end a second guiding channel 12 of V shape for guiding the sewing needle of the sewing machine (Fig. 7) formed by cutting off the sides of the channel in the forward end from the top to the bottom in inclined direction. The needle guiding plate is arranged to incline downwardly to its forward end.

The hook-needle 10 has a hook portion 13 at the forward end which hook portion is formed by bending upwardly at a proper angle and then downwardly to have an opening facing downwardly, and an eye portion 14 at the rearward end. The hook-needle 10 is pivotally mounted by the eye portion 14 on the pin 9 of the slider 6 and is prevented from slipping out of the pin by a knob 15 screwed thereon. A coil spring 16 is loosely mounted on the pin 9 and is engaged at one end with the hook-needle 10 and fixed at the other end to the slider 6, so that it will tend to rotate the hook-needle about the pin thereby raising the forward end thereof upwardly.

Thus the hook-needle 10 is normally held in the retracted position as shown in Fig. 1 in such a manner that only the upper edge of the hook portion 13 is kept in contact with the top of the first guiding channel 11, but may be advanced forwardly when the slider 6 is pushed forward along the slot 7 against the action of the spring 8 by applying a manual force on the knob 15 of the slider 6.

The mounting member indicated by the reference numeral 2 comprises a cylindrical mounting tube 17, a cylindrical sleeve 18 which is rotatably set in said cylindrical mounting tube and is adapted to be fixed on a pressure-bar 19 of the sewing machine by means of a set screw 20, and a supporting arm 21 which projects outward from said cylindrical mounting tube and has a bracket 22 fixed thereon, to which is pivotally mounted an upper portion 23 of the above-mentioned supporting plate 4 of the threader proper 1. A pressing pin 24 having a head 25 is mounted in the supporting arm 21, said head 25 always applying a pressure on the upper portion 23 of the supporting plate 4.

On the bracket 22 of the supporting arm 1 is provided a stop 27, which acts to stop the supporting plate 4 which is urged downward by the action of the spring 26 when said supporting plate 4 is lowered, whereby the supporting plate 4 is held at a predetermined angle as required, as shown in full lines in Fig. 5.

Now the manner how the above mentioned needle threader according to one form of the present invention can be used will be explained as follows. The needle threader is mounted on the pressure-bar 19 of the sewing machine, by fitting the sleeve 18 of the mounting member 2 on said pressure-bar and then fixing said sleeve at the proper position along the length of the pressure-bar by the set screw 20. When the needle threader is not used, the threader is rotated as a whole around the mounting sleeve 18 backwardly of the sewing machine and the threader proper 1 is raised upward as shown in Fig. 4. The threader proper 1 is then held in the raised position or resting position by the action of the spring 26 (Fig. 5).

When it is desired to use the needle threader, the threader proper 1 is lowered into the position shown by full lines in Fig. 5 and then the threader is rotated as a whole around the sleeve 18 forwardly of the sewing machine until it comes to the operative position shown in Fig. 2. In this position, the second guiding channel 12 of the guiding plate 5 is pressed into contact with a sewing-needle 28 of the sewing machine, thus guiding the needle 28. Then the slider 6 carrying the hook-needle is advanced against the force of the spring 8 by applying a manual force on the knob 15. At this time the hook portion 13 of the hook-needle 10 is lightly pressed into contact with the first guiding channel 11 of the needle guiding plate 5 as shown in Fig. 8, so that the hook portion 13 is guided by said channel 11, while advancing, and comes in contact with the sewing-needle 28 as shown by full lines in Fig. 9. Then the hook portion 13 is guided by a groove 29 provided in the sewing-needle adjacent to an eye 30 thereof, until the hook portion slides into the eye 30 of the sewing-needle.

When the hook portion 13 of the hook-needle has passed through the eye 30 of the sewing-needle, a thread to be passed through the eye is engaged in the hook portion, and then the hook-needle is retracted by the action of the spring 8, carrying the thread through the eye. Thus the thread is passed through the eye of the sewing-needle and the threading operation is completed. After completion of the threading operation, the threader will be rotated and raised into the resting position as aforementioned.

According to the present invention as described with reference to the drawings, there is no danger of bringing about a misalignment in the required relative position between the sewing-needle and the hook-needle, because the forward end of the top of the first guiding channel 11 is made to conform to the apex of the second guiding channel 12 so that the guiding points of these channels for the hook-needle and the sewing needle are the same front point of the guiding plate 5, and because the hook portion of the hook-needle is bent upward so that only the upper edge of said hook portion is kept in contact with the first guiding channel, the other part of the hook needle not contacting with said channel, whereby the hook portion at the forward end of the hook-needle is guided until it will enter into the groove of the sewing needle.

Thus the needle threader according to the present invention assures that the hook portion of the hook-needle can be inserted easily and accurately into the eye of the sewing needle, even if the hook-needle is somewhat bent, and consequently it assures that a thread can be inserted into the eye of the sewing-needle without fail.

The needle threader as described above is so arranged that the hook-needle engages the groove of the sewing-needle in a little inclined position downwardly to the front and slides along said groove until the hook portion of the hook-needle slides into the eye of the sewing-needle, and the hook needle is formed with the upwardly bent hook portion having the bending angle of such value as corresponds to the inclining angle of the hook-needle when the hook portion enters into the eye of the sewing

needle. Thus the hook portion of the hook-needle passes the eye of the sewing-needle substantially at right angle with respect to the sewing-needle.

Accordingly this needle threader permits to use a relatively large vertical width of the hook portion (as indicated by b in Fig. 6) as compared with the case in which the hook portion of the hook-needle is adapted to diagonally pass through the eye (in the case of the present invention, the vertical width a little smaller than the length of the eye of the sewing-needle will suffice), and therefore the hook-needle can be manufactured more easily.

While one embodiment of the present invention has been shown and described it will be apparent that other modifications and alterations may be made without departing from the scope of the invention.

I claim:

1. A needle threader for a sewing machine having a sewing needle, comprising a threader body, means for mounting the threader body on the sewing machine, a hook-needle support slidably mounted on said threader body, a hook-needle pivoted on said support and including an upwardly bent hook portion, a needle guiding plate provided on said threader body and inclined downwardly therefrom, a first guiding channel on said needle guiding plate for guiding the hook portion of said hook-needle, spring means for resiliently pressing said hook portion into contact with the first guiding channel, and a second guiding channel at the forward end of said needle guiding plate for guiding the sewing needle of the sewing machine.

2. A needle threader for a sewing machine according to claim 1, in which the upwardly bent hook portion of the hook-needle is at an angle which corresponds to the angle of inclination of the hook-needle with the hook portion entering into the eye of the sewing needle.

3. A needle threader for a sewing machine, comprising a threader body, means supporting the threader body on the sewing machine, a hook-needle support slidably mounted on said threader body, a hook-needle pivoted on said support and including an upwardly bent hook portion, a needle guiding plate on said threader body and inclined downwardly therefrom, a first guiding channel on the needle guiding plate to guide the hook-needle, spring means for resiliently pressing said hook-needle into contact with the first guiding channel, and a second guiding channel on the needle guiding plate to guide the needle at a point which lies at an end of the first guiding channel.

4. A needle threader according to claim 3, in which the first guiding channel is an inverted V groove on the underside of the needle guiding plate which is adapted to guide the upwardly bent hook portion of the hook-needle, and the second guiding channel is a V-shaped notch having the apex lying at an end of the first guiding channel and which is adapted to guide the needle at said apex.

5. A needle threader according to claim 4, in which the second guiding channel is connected with the first guiding channel.

6. A needle threader according to claim 3, in which the spring means comprises a coil spring loosely mounted on the pivot of the hook-needle and engaged at one end with the hook-needle and fixed at the other end to the support.

7. A needle threader according to claim 3, in which said spring means resiliently urges the support into position to hold the hook-needle carried on the support in retracted position.
